UNITED STATES PATENT OFFICE.

TALBOT C. DEXTER, OF PEARL RIVER, NEW YORK.

PAPER-FEEDING MACHINE.

No. 886,118.

Specification of Letters Patent.

Patented April 28, 1908.

Application filed August 3, 1907. Serial No. 336,867.

To all whom it may concern:

Be it known that I, TALBOT C. DEXTER, a citizen of the United States, and a resident of Pearl River, in the county of Rockland and State of New York, have invented certain new and useful Improvements in Paper-Feeding Machines, of which the following is a specification.

My present invention relates generally to improvements in paper feeding machines, and particularly to feeding machines of the sheet combing type, in which the pile of sheets is acted upon by combing feeding devices which comb or feather out the top sheets of the pile to gradually separate the successive sheets near the top so that they may be drawn from the pile periodically and fed to any machine arranged to operate upon the individual sheets. Machines of this type are set forth in Letters Patent No. 829,854, granted to me August 28th, 1906, and No. 850,821, granted April 16th, 1907.

My present invention is an improvement upon the structure set forth in an application for patent filed by me August 1st, 1907, Serial No. 386602, and the object of my present invention is to further improve the construction and operation of this type of mechanism.

My present invention involves the same general principle as the mechanism covered by my said application Serial No. 386602, in that the sheet actuated tripping finger carries and operates a wedging blade or plate which is projected between two co-operating rollers, one of which is mounted upon a movable support connected with the tripping finger of the latching mechanism. The main feature of distinction over the machine of said prior application is the mounting of the sheet actuated controlling mechanism. In my present improvement I have mounted both of the co-operating rollers and the tripping finger upon a movable support which is periodically operated by cam mechanism through a link or pitman having lost motion connection with said movable support so that the periodic elevation of the tripping finger out of the path of the sheets is accomplished by raising the said movable support. The lost motion connection of this cam operated link or pitman with the movable support of the tripping mechanism is for the purpose of

enabling said link or pitman to first trip the latching mechanism and then elevate the tripping finger out of the path of sheets.

In order that my invention may be fully understood, I will first describe the same with reference to the accompanying drawings, and afterwards point out the novelty more particularly in the annexed claims.

Figure 1 is a detail vertical transverse sectional elevation of one half of a paper feeding machine embodying my invention, the other half of the machine being omitted. Fig. 2 is a top plan view of the same. Fig. 3 is a vertical longitudinal sectional view of the same, taken on the line *a*—*a* of Figs. 1 and 2, looking in the direction indicated by the arrows *a*, *a*. Fig. 4 is a similar view taken on the line *b*—*b* of Figs. 1 and 2, looking in the direction indicated by the arrows *b*, *b*. Fig. 5 is a detail vertical longitudinal sectional view, on a larger scale, taken on the line *c*—*c* of Figs. 1 and 2 and looking in the direction indicated by arrows, *c*, *c*, showing the main parts in tripped position, and omitting some parts for clearness. Fig. 6 is a detail sectional view.

Sheet feeding machines of the type to which my present invention relates are provided with two sets of sheet moving devices arranged to operate at opposite sides of the machine. In the accompanying drawings, I have shown only one half of the machine, including only one of these sheet moving devices, but it will be understood that two such devices of the same construction are employed, each being independently controlled by a sheet actuated tripping device, as hereinafter explained.

The frame-work of my improved machine may be of any suitable construction to properly support the working parts hereinafter referred to. In the drawings, 1 represents one of the vertical side frames. The side frames are suitably braced to make them rigid by means of stay rods 2, 3, and other frame parts not shown, and within the frame is provided a suitable table or support (not shown) for carrying a pile of sheets, indicated by the reference letter *P*. At the front of the pile of sheets, I provide a series of vertical guide rods or strips, (not shown) for confining the pile. 4 is a constantly driven shaft bearing the

lower feed rollers 6 and 7, said shaft 5 being braced at intervals by suitable bearing brackets, (not shown). 8 are drop rollers journaled in the rock arms 9, mounted upon the transverse rock shaft 10. The drop rollers 8 are supported above two or more of the under feed rollers 6, with which they coöperate. The rock shaft 10 extends transversely of the machine, above the constantly running lower shaft 5, and is suitably braced between its ends by two or more bracket arms, (not shown), rigidly secured to the auxiliary longitudinal frame pieces 12. The rock shaft 10 is operated by any of the usual forms of mechanism, such, for instance, as shown in my above-named patents, whereby the drop rollers 8 are periodically lowered and raised into and out of engagement with the coöperating under rollers 6, for performing their function of feeding off the successive sheets.

The main cam shaft 20 extends transversely of the machine and is suitably journaled in the main side frames 1 and the auxiliary longitudinal frame pieces 12. This shaft 20 is provided with a driving pulley 25, as shown, or it may be driven in any other suitable manner, said shaft being the shaft from which all other parts of the machine are driven. The cam shaft 20 carries a large gear 26, which meshes with a smaller gear (not shown) secured to a larger gear 28, journaled upon a stud 29, projecting from the side frame of the machine. The gear 28 meshes with and drives a small intermediate gear (not shown) which in turn drives a small gear 32 keyed to the projecting end of the combing driving shaft 35, hereinafter referred to, and another smaller gear (not shown) keyed to the projecting end of the constantly rotating feed shaft 5 above referred to. This gearing is clearly shown and described in my above named patents.

40 is one of a pair of combing wheels. 45 Each of these combing wheels is freely journaled at 41 upon a rock arm 42, which is freely journaled upon a sleeve 50 which is in turn journaled upon the shaft 35. This shaft 35 has keyed to it a gear 45 which 50 meshes with a gear 46 secured to the combing wheel 40, by which the combing wheel is constantly rotated.

Projecting from one face of the combing supporting rock-arm is an integral lug 43 in which is mounted an adjustable tappet screw 44. Secured upon the sleeve 50 to one side of the rock arm 42 is a rock arm 51 which is provided with a finger 52, which projects beneath the tappet screw 44 just referred to, and by its engagement therewith lifts the combing wheel away from the pile. By adjusting the screw 44, the limits of rise and fall of the combing wheel can be fixed. The rock-arm 51 is moved in one direction for 65 lifting the combing wheel by a spring mech-

anism which is normally restrained by a latching device which is periodically released by the sheet actuated tripping device herein-after explained. The rock-arm 51 is moved in the opposite direction to allow the combing wheel to move by gravity into engagement with the pile of sheets by the action of a cam as will now be explained. Sleeve 50 has at its end, adjacent to the rock-arm 51, another rock-arm 55 to which is pivotally connected a pitman 56, formed with a yoke-shaped upper end, which straddles the shaft 20. The shaft 20 carries a peripheral cam 58, which engages an antifriction roller 57 journaled upon the pitman 56, whereby the 70 rock-arm 56, sleeve 50, and finger 52 are moved once in each revolution of the shaft 20 to reset the spring and latching mechanisms (hereinafter described) and allow the 75 combing wheel to rest upon the pile.

The rock-arm 51 projects forwardly from the sleeve 50 and has pivotally connected to its forward end a latching bar 60 extending vertically and riding, in its upper end, in a socket formed in a bracket 62 extending laterally from one of the central auxiliary frames 12. Freely journaled upon a pin or bolt 65 projecting laterally from the latching bar 60 is an antifriction roller 64, which normally engages the upper end of a latching 90 arm 63 freely journaled upon a bolt 66 mounted in bracket arm 67 of the movable support for the tripping mechanism herein-after described. When the latching arm 63 is in engagement with the antifriction roller 100 64, said arm will be in proper position to maintain the downward thrust of the latching bar to withstand the pressure of the spring device (presently to be referred to), with the result that the combing wheel will 105 be allowed to rest in its lower operating position. The latching arm 63 is moved into and out of active position during the operation of the machine by the means herein-after described, its movement out of action being 110 normally under the control of the sheets fed from the pile.

A rod 70 is pivoted at 71 to the rock arm 51 and projected therefrom vertically through the guide bracket 62. Surrounding 115 the rod 70 and confined between a collar 70^a above the rock arm 51 and the guide bracket 62 is an expansion spring 75 which tends to throw down the arm 51 and move up the finger 52 for raising the combing wheel away from the 120 pile of sheets. This spring tendency is normally restrained by the latching arm 63, and the latching bar 60.

Turning now to the sheet controlled tripping mechanism for releasing the combing 125 elevating means, it will be observed that a rock arm 67 is supported upon the combing operating shaft 35. The hub portion 67^a of the rock arm 67 is cut out at 67^b to receive a laterally projecting pin 68 extending from 130

a bearing collar of the downwardly projecting bracket of the frame piece 12 in which shaft 35 is journaled, (see Fig. 6). By this means the rock arm is rigidly supported in approximately horizontal position, and is at the same time permitted a limited upward movement upon the shaft 35.

A short shaft 80 is freely journaled in the forward end of the rock arm 67, and carries a rubber faced roller 81 and a relatively large gear wheel 82, said roller 81 and gear 82 being rigidly secured upon the shaft 80 so as to revolve therewith. The gear 82 meshes with one of the train of gears 83, 84 and 85, the intermediate gears 83 and 84 of which train are freely journaled at 86 and 87 upon the rock arm 67, while the driving gear 85 of said train is keyed to the comber operating shaft 35. By this mechanism the roller 81 is caused to travel constantly in the direction indicated by the arrow in Fig. 5 of the drawings.

Freely journaled upon the bolt 66 which supports the tripping arm 63 is a rock arm 90 projecting forwardly and carrying in its forward end a freely journaled rubber faced roller 91 which is supported directly above the constantly running lower roller 81, and, in the normal operative position of the machine, runs in peripheral contact with and is driven by said roller 81. The forwardly projecting rock arm 90 is formed integral with or rigidly secured to a tubular hub 92 which journals upon the bolt 66, and is formed at one end with the upwardly projecting arm 93 formed with the laterally projecting fingers 94 which project in front and rear of the tripping arm 63. The arm 93 is formed with a horizontal slot 95 through which passes an adjusting set screw 96 which is threaded into a suitable opening formed in the trip arm 63. The purpose of the slot 95 and set screw 96 is to adjust the relation of tripping arm 63 and roller rock arm 90 so as to accurately present the tripping arm 63 beneath the antifriction roller 64 of tripping bar 60, for supporting said tripping bar, when the roller 91 is in peripheral contact with the roller 81. The movement of the roller 91 into contact with the roller 81, moves the tripping arm 63 forwardly to bring it beneath the antifriction roller 64 on the tripping bar. To prevent the possibility of the tripping arm 63 moving too far forward beneath the roller 64 (which might render it difficult to trip the arm 63 from beneath the roller) I provide a stop plate or lug 60^a upon the tripping bar 60. This lug 60^a projects across the path of the tripping arm 63 and limits its forward movement so as to accurately arrest it vertically beneath the antifriction roller 64.

It will be understood from the description thus far given that the tripping arm 63 is tripped from beneath the roller 64 on the tripping bar 60 by the upward movement of the

rock arm 90. This tripping action is accomplished by means of a sheet actuated tripper which will now be explained.

100 is the tripping finger depending from and freely journaled upon a pin or bolt 103 projecting horizontally and laterally from a boss 102 which is secured to the face of a downward extension 67^a of the rock arm 67, by which said journal pin 103 is supported. The lower end of the tripping finger 100 is shaped so as to present a vertical face 100^a across the plane of feed of the sheets, when the tripping finger is in tripping position. Projecting upwardly from and formed integral with the tripping finger, is an arm 105 which carries at its upper end a laterally projecting wedge-shaped blade or plate 106. The journal pin 103 is directly beneath the short shaft 80, and the length of the arm 105 is such that the blade or plate 106 will be presented in proper position to pass over the upper periphery of the constantly rotating roller 81, the roller 81 being designed to frictionally engage the under surface of the blade 106, when it is moved into contact therewith, for the purpose of causing said blade to pass over the roller 81 and under the roller 91 for elevating roller 91 and rock shaft 90 for tripping the arm 63. It will be understood that this action takes place when the leading edge of a sheet moving from the pile engages the tripping finger and moves the blade or plate 106 into the bite of the rollers 81 and 91.

Keyed to the main cam shaft 20 is a cam 119 having a high portion and a low portion, each of which portions is about one-half the circumference of the cam.

116 is a rock arm journaled at 117 and carrying a freely journaled antifriction roller 118, which runs in peripheral contact with the controlling cam 119. Pivoted to the outer end 115 of the rock arm 116 is a downwardly extending rod or pitman 113 whose lower end is provided with two vertical slots 113^a and 113^b, into which the extended ends of the shafts 91^a and 80 project. The upper slot 113^a is of greater length than the lower slot 113^b for the purpose which will presently appear.

While the antifriction roller 118 is in engagement with the low portion of the controlling cam 119, the movable support or rock arm 67 for the tripping mechanism will be in its lowered position, with the tripping finger resting in the path of the sheets in readiness to be operated by the leading edge of the sheet. In this position, which is shown in Fig. 4 of the drawings, the wedging blade or plate 106 is supported directly in front of the coöperating rollers 81 and 91. When the roller 118 passes to the high portion of the controlling cam 119, it will be observed that the rod or pitman 113 will be moved upwardly with the result that the roller 91 will first be moved away from the

roller 80, (unless the previous tripping action of the sheet has elevated the roller 91) for actuating the tripping arm 63, and then the rock arm 67 will be raised by the engagement 5 of the lower end of lower slot 113^b with the shaft 80, the result being that the tripping finger 100 will be raised above the path of the sheets as shown in Fig. 5 of the drawings. This action will be more fully understood in 10 connection with the complete operation of the machine as hereinafter explained. It should be observed, however, in this connection that in the position of the parts as shown in Fig. 4 when the machine is operating 15 and the tripping mechanism is in readiness to be tripped by the action of the sheet, the upper end of slot 113^b is resting upon the shaft 80, and the lower end of the upper slot 113^a is in engagement with the shaft 91. 20 This relative arrangement is to permit the upward movement of rod or pitman 113 to raise the roller 91 before the rock arm 67 is moved, the position of lower slot 113^b in Fig. 4 being such that the pitman will have 25 a preliminary upward movement relatively to shaft 80 before engaging said shaft for moving rock arm 67.

As described above the lower constantly running shaft is provided with the ordinary under-feed rollers 6 and the special under-feed rollers 7. These rollers 7, two of which are provided in the machine, are in the form of twin rollers, with an annular groove or recess 7^a separating the two parts. The 35 same result can, of course, be accomplished by mounting two separate rollers upon the shaft 5 with a sufficient space between them. The twin rollers 7 are mounted upon the shaft 5 directly beneath the tripping fingers 40 100 so that the lower sheet engaging portion 100^a of each tripping finger will project into the annular groove or recess 7^a of the under twin rollers. This is clearly shown in Fig. 1 of the drawings.

Coöperating with the under twin rollers 7 are the auxiliary drop rollers 125 which are also arranged as twin rollers or as pairs of independent rollers. These drop rollers 125 are freely journaled at 126 upon the forward 50 ends of rock arms 127 pivoted at 128 upon the downwardly projecting bracket arms 129 extending below the comber operating shaft 35 and supported from one of the main brackets which is mounted upon one of the central frame pieces 12. Projecting rearwardly 55 from each rock arm 127 is a finger 130 carrying a laterally projecting pin or lug 131 upon which is pivoted the lower end of a rod or pitman 133 which is pivotally connected at 60 its upper end with a rock arm 135 mounted upon a rock shaft 136 which passes through and is freely journaled upon suitable bearings in the main bracket 67 and an auxiliary bracket 137 secured thereto. The rock 65 shaft 136 has secured to its opposite end

a rock arm 138 to the free end of which at 139 is pivoted a downwardly projecting link 140 which is pivotally connected at its lower end with the rock shaft 51 by which the combing wheel is raised and lowered. From this arrangement it will be observed that when the combing wheel is raised away from the pile of sheets, the auxiliary twin drop rollers 125 will also be raised.

It will be observed particularly with reference to Fig. 1 of the drawings that the leading edge of the sheet which engages and actuates the tripping fingers 100 is firmly supported upon both sides of each tripping finger and positively fed by the under twin rollers 7 and the upper twin drop rollers 125. This provides a very effective gaging edge for actuating the tripping fingers.

Extending longitudinally of the machine, at each side is a rock shaft 155 journaled in 85 bracket arms 156 extending down from the auxiliary frame pieces 12. At the forward end of each of these rock shafts is a rock arm 157 carrying at its upper end an antifriction roller 158, which operates in engagement with 90 a face cam 159, keyed to the cam shaft 20. Each of the rock shafts 155 carries a horizontal rock arm which is adjustable longitudinally of the machine, and carries a weighted 95 tail gripper 160 of the same construction as fully set forth in my above named patents.

The following brief explanation will make clear the operation of my improved machine: It being understood that a machine embodying my improvements is provided with two 100 sets of sheet combing mechanisms, each independently controlled by a sheet actuated tripping device as described, the machine is started in operation and the combing wheels lowered upon the top of the pile of sheets, the 105 combing wheels being driven through the gears as above explained. In this normal operative position of the machine, the spring elevating mechanisms for the combers are held out of action by the latching arms 63 and latching bars 60, the rollers 91 being in peripheral contact with and driven by the 110 constantly running rollers 81, and the tripping fingers 100 with their controller blades or plates 106 being in normal position as 115 shown in Fig. 4 of the drawings. In this starting position of the machine, the main drop rollers 8 are elevated away from the ordinary under feed rollers 6, and the auxiliary twin drop rollers 125 are running in peripheral contact with the under twin rollers 7. The tail grippers 160 are held out of contact 120 with the pile.

The two combing wheels will continue to operate until the forward edge of the top 125 sheet in front of one of the combing wheels is moved forward sufficiently to engage and actuate one of the tripping fingers 100. In a combing machine in which a number of the sheets at the top of the pile are gradually sep- 130

arated and shifted forwardly, the combing wheels operate but a moment to shift the top sheet into registered position. The instant that the sheet engages one of the tripping fingers, the actuated tripping finger will cause the plate or blade 106 connected therewith to enter between the rotating rollers 81 and 91, with the result that the roller 91 will be raised sufficiently to cause latching arm 63 to be moved from beneath the roller 64 of one of the latching bars 60, which frees the spring device and permits it to instantly act upon the rock arm 51 for elevating the combing wheel away from the pile of sheets and arrests the action of the particular combing wheel upon the sheets. This upward movement of the roller 91 under the action of the tripping finger is permitted by the slot 113^a in the rod or pitman 113, as shown in Fig. 4 of the drawings. This action is immediately followed by the same operation on the other combing wheel, as the edge of the sheet in front of such other combing wheel reaches registered position and actuates the other tripping finger.

When both combing wheels have been arrested by these independent sheet actuated tripping devices, the sheet will be found to be in registered position in readiness for the operation of the delivery drop roller mechanism, which comes into play to feed the registered sheet from the pile of the feeding machine and deliver it to the printing press folding machine or other machine which is to operate upon the sheets. In the normal operation of the feeding machine, it will be found that both combing wheels are thrown out of operation at approximately the same time, there usually being but slight variations in the position of the sheets upon the pile. Each of the auxiliary twin drop rollers 125 is moved into and out of operative position simultaneously with the combing wheel in front of which it operates. As the successive sheets are engaged and fed off by the delivery drop roller mechanism, the tail grips 160 engage the under sheet of the pile just back of the rear edge of the top sheet for holding the pile in place. Coincident with the operation of the delivery drop roller, the high portions of controlling cams 119 engage the antifriction rollers 118 of rock arms 116 and cause the upward movement of rods or pitmen 113 for elevating the movable supports or rock arms 67 of the tripping mechanism. When the rock arms 67 are raised the tripping fingers 100 will be supported above the path of the sheet being delivered, so as to entirely relieve the sheet from its engagement with the tripping fingers. This position of the parts is shown in Fig. 5 of the drawings. In this action of the controlling cams, it will be understood that the first upward impulse of rod or pitman 113 takes up the lost motion occasioned by the slot 113^b,

so as to permit the tripping of the latch mechanism before the arm 67 is raised, in the event that such action has not already occurred by the action of the sheet. The parts remain in this tripped position until the sheet has entirely passed out of the machine, when by the action of the controlling cams, the parts are returned to their operative position, it being understood that simultaneously with the return of the tripping mechanisms to their normal operative position, the cams 58 will forcibly rock the sleeves 50 to permit the combing wheels 40 to again fall into operative engagement with the top of the pile of sheets, and to compress the springs 75 and reset the latching mechanisms.

There are two important advantages in the construction covered by my present application over the structure of my above named application Serial No. 386,602. In the first place the present structure is simpler and more economical to manufacture, and in the second place the improved structure permits greater rapidity in the delivery of sheets from the machine because the action of moving the tripping fingers out of the path of the sheets in a vertical direction is more direct than the action in the machine of said former application, in which the tripping fingers are moved upon their journals.

With the exception of the operation of the tripping mechanism by the cam mechanism, the principles involved in the present machine are substantially the same as those covered by my aforesaid application Serial No. 386,602, and the machine of the present case is, therefore, subject to many of the claims found in said former application.

What I claim is:

1. The combination of a sheet moving instrument, means for operating said instrument, and arresting means for holding said instrument out of operation, with a sheet actuated tripping finger supported in the path of sheets and arranged to trip said arresting means, a movable support for said tripping finger, and means for periodically raising and lowering said tripping finger support for moving the tripping finger into and out of the path of sheets.

2. The combination of a sheet moving instrument, means for operating said instrument, and arresting means for holding said instrument out of operation, with a sheet actuated tripping finger supported in the path of sheets, a movable support for said tripping finger, tripping means operated by said finger and arranged to control said arresting means, and means for periodically raising said tripping finger support and actuating said tripping means independently of said finger.

3. The combination of a sheet moving instrument, means for operating said instru-

- ment, and means for arresting the operation of said instrument including latching mechanism, with means for tripping said latching mechanism including a tripping finger supported in the path of sheets, a movable support for said tripping finger, and mechanism for periodically raising and lowering said movable support.
4. The combination of a sheet moving instrument, means for operating said instrument, and means for arresting the operation of said instrument, with means for tripping said arresting means including a tripping finger supported in the path of sheets, a movable support for said tripping means, and mechanism for periodically raising said movable support and actuating said tripping means independently of said tripping finger.
5. The combination of a sheet moving instrument, means for operating said instrument, and means for arresting the operation of said instrument including a latching bar and a coöperating latching arm, with means for tripping said latching arm including a tripping finger supported in the path of sheets, a movable support for said tripping means, and an actuated mechanism for periodically raising and lowering said movable support.
6. The combination of a sheet moving instrument, means for operating said instrument, and means for arresting the operation of said instrument including a latching bar and a coöperating latching arm, with means for tripping said latching arm including a tripping finger supported in the path of sheets, a movable support for said tripping means, and mechanism for periodically raising said movable support, and actuating said latching arm independently of said tripping finger.
7. The combination of a sheet moving instrument, means for operating said instrument, and means for arresting the operation of said instrument, a rock arm movable toward and away from the sheet support, sheet actuated tripping mechanism mounted upon said rock arm, a tripping finger included in said tripping mechanism and supported by said rock arm in the path of sheets, and means for raising and lowering said rock arm.
8. The combination of a sheet moving instrument, means for operating said instrument, and means for arresting the operation of said instrument including a latching bar and a coöperating latching arm, a rock arm movable toward and away from the sheet support, sheet actuated tripping mechanism mounted upon said rock arm, a tripping finger included in said tripping mechanism and supported by said rock arm in the path of sheets, and means for periodically raising and lowering said rock arm and tripping said latching arm independently of said tripping finger.
9. The combination of a sheet moving instrument, means for operating said instrument, and means for arresting the operation of said instrument including latching mechanism, a rock arm movable toward and away from the sheet support, sheet actuated tripping mechanism mounted upon said rock arm, a tripping finger included in said tripping mechanism and supported by said rock arm in the path of sheets, and means for raising and lowering said rock arm, including a part adapted to engage and actuate said latching mechanism independently of said tripping finger.
10. The combination of a sheet moving instrument, means for operating said instrument, and means for arresting the operation of said instrument including a latching bar and a coöperating latching arm, a rock arm movable toward and away from the sheet support, sheet actuated tripping mechanism mounted upon said rock arm, a tripping finger included in said tripping mechanism and supported by said rock arm in the path of sheets, and means for raising and lowering said rock arm including means of engagement with said latching arm.
11. In a paper feeding machine, the combination of a sheet moving instrument, means for operating the sheet moving instrument, means for arresting the operation of said instrument, a rock arm movable toward and away from the sheet support, a latching arm mounted upon said rock arm and controlling said arresting means, sheet actuated tripping mechanism mounted upon said rock arm and including a tripping finger supported normally in the path of sheets, and means for raising and lowering said rock arm.
12. In a paper feeding machine, the combination of a sheet moving instrument, means for operating the sheet moving instrument, means for arresting the operation of said instrument, a rock arm movable toward and away from the sheet support, a latching arm mounted upon said rock arm and controlling said arresting means, sheet actuated tripping mechanism mounted upon said rock arm and including a tripping finger supported normally in the path of sheets, means for raising and lowering said rock arm, and means operated by said raising and lowering means for tripping said latching arm independently of the sheet actuated tripping finger.
13. In a paper feeding machine, the combination of a sheet moving instrument, means for operating the sheet moving instrument, means for arresting the operation of said instrument, a latching bar controlling said arresting means, a rock arm movable toward and away from the sheet support, a latching arm mounted upon said rock arm and coöperating with said latching bar, sheet actuated tripping mechanism mounted upon

said rock arm and including a tripping finger supported normally in the path of sheets, means for raising and lowering said rock arm, and means of engagement between the raising and lowering means and the latching arm for tripping said latching arm independently of the sheet actuated tripping finger.

14. The combination of a sheet moving instrument, means for operating said instrument, means for arresting the operation of said instrument, means normally restraining said arresting means, a movable support, a rock arm mounted upon said movable support and arranged to trip said arresting means, sheet actuated means mounted upon said movable support for operating said rock arm, means for raising said movable support, and means actuated by said raising means for operating said rock arm.

20 15. The combination of a sheet moving instrument, means for operating said instrument, means for arresting the operation of said instrument, a latching bar and a co-operating latching arm normally restraining said 25 arresting means, a movable support upon which said latching arm is journaled, a rock arm connected with said latching arm, sheet-actuated means mounted upon said movable support for operating said rock arm to trip 30 the latching arm, means for raising said movable support, and means actuated by said raising means for operating said rock arm.

16. The combination of a sheet moving instrument, means for operating said instrument, means for arresting the operation of said instrument, means normally restraining said arresting means, a movable support, a rock arm mounted upon said movable support and arranged to trip said arresting 40 means, sheet actuated means mounted upon said movable support for operating said rock arm, means for raising said movable support, including a reciprocating rod or pitman suitably connected therewith, and a connection 45 between said rod or pitman and said rock arm.

17. The combination of a sheet moving instrument, means for operating said instrument, means for arresting the operation of said instrument, means normally restraining said arresting means, a movable support, a rock arm mounted upon said movable support and arranged to trip said arresting means, sheet actuated means mounted upon 55 said movable support for operating said rock arm, a reciprocating rod or pitman having pin and slot connection with said movable support and pin and slot connection with said rock arm, and means for operating said 60 rod or pitman.

18. The combination of a sheet moving instrument, means for operating said instrument, means for arresting the operation of said instrument, means normally restraining 65 said arresting means, a movable support, a

rock arm mounted upon said movable support and arranged to trip said arresting means, a tripping roller journaled upon said rock arm, a tripping finger journaled upon said movable support, a tripping blade connected with the tripping finger, a rod or pitman having lost motion connections with said rock arm and said movable support, and a cam arranged to actuate said rod or pitman.

19. The combination of a sheet moving instrument, means for operating said instrument, means for arresting the operation of said instrument, a latching bar and a co-operating latching arm normally restraining said arresting means, a movable support upon 80 which said latching arm is journaled, means for limiting the movement of said support in one direction, a rock arm connected with said latching arm, sheet actuated means mounted upon said movable support for operating said rock arm to trip the latching arm, and means for raising and lowering said movable support.

20. In a paper feeding machine, the combination of a sheet moving instrument, 90 means for operating the sheet moving instrument, means for arresting the operation of said instrument, a latching bar controlling said arresting means, a rock arm movable toward and away from the sheet support, 95 means for limiting the movement of said rock arm toward said sheet support for sustaining said rock arm in its lowered position, a latching arm mounted upon said rock arm and co-operating with said latching bar, sheet 100 actuated tripping mechanism mounted upon said rock arm and including a tripping finger supported normally in the path of sheets, and means for raising and lowering said rock arm.

21. In a paper feeding machine, the combination of a sheet moving instrument, means for operating the sheet moving instrument, means for arresting the operation of said instrument, a latching bar controlling said arresting means, a rock arm movable 110 toward and away from the sheet support, means for limiting the movement of said rock arm toward said sheet support for sustaining said rock arm in its lowered position, a latching arm mounted upon said rock arm 115 and co-operating with said latching bar, sheet actuated tripping mechanism mounted upon said rock arm and including a tripping finger supported normally in the path of sheets, means for raising and lowering said 120 rock arm, and means operated by said raising and lowering means for tripping said latching arm independently of the sheet actuated tripping finger.

22. The combination of a sheet moving instrument, with means for operating said instrument, including a rotary shaft, a rock arm mounted upon said shaft, a constantly running roller journaled upon said rock arm, gearing between said constantly running 130

- 8
 roller and said shaft, a coöperating tripping roller, an arm journaled upon said rock arm and supporting said tripping roller in operative relation to said constantly running roller, means for arresting the operation of the sheet moving instrument, a coöperating latching bar and latching arm normally restraining said arresting means, said latching arm being connected with the supporting arm of the tripping roller, a sheet actuated tripper mounted upon said rock arm and supported thereby in the path of sheets, and means for raising and lowering said rock arm.
- 15 23. The combination of a sheet moving instrument, with means for operating said instrument, a rock arm, means for limiting the movement of said rock arm, a constantly running roller journaled upon said rock arm, a coöperating tripping roller, an arm journaled upon said rock arm and supporting said tripping roller in operative relation to said constantly running roller, means for arresting the operation of the sheet moving instrument, a coöperating latching bar and latching arm normally restraining said arresting means, said latching arm being connected with the supporting arm of the tripping roller, a sheet actuated tripper mounted upon said rock arm and supported thereby

in the path of sheets, a rod or pitman formed with slots which engage the shafts or journals of said tripping roller and constantly running roller, and a cam mechanism for operating said rod or pitman.

35

24. The combination of a sheet moving instrument, with means for operating said instrument including a rotary shaft, a rock arm mounted upon said shaft, means for limiting the movements of said rock arm, a constantly running roller journaled upon said rock arm, gearing between said constantly running roller and said shaft, a coöperating tripping roller, an arm journaled upon said rock arm and supporting said tripping roller in operative relation to said constantly running roller, means for arresting the operation of the sheet moving instrument, means normally restraining said arresting means, a sheet actuated tripper mounted upon said rock arm and supported thereby in the path of sheets, a rod or pitman formed with slots which engage the shafts or journals of said constantly running roller, and a cam mechanism for operating said rod or pitman.
